UNITED STATES PATENT OFFICE.

JOHN SUTHERLAND, OF SPRINGER, TERRITORY OF NEW MEXICO.

BOX.

No. 823,823.

Specification of Letters Patent.

Patented June 19, 1906.

Application filed August 4, 1905. Serial No. 272,691.

To all whom it may concern:

Be it known that I, JOHN SUTHERLAND, a citizen of the United States, and a resident of Springer, in the county of Colfax and Territory of New Mexico, have invented a new and Improved Box, of which the following is a full, clear, and exact description.

This invention relates particularly to improvements in boxes for holding granulated tobacco, the object being to provide a box approximating the size of the original package or bag, so that the tobacco may be transferred from the bag to the box and maintain practically its original shape without danger of being pulverized as it does when carried in a bag.

Figure 1 is a perspective view of the box embodying my invention. Fig. 2 is a longitudinal section thereof. Fig. 3 is an inside view of the main cover, and Fig. 4 shows in perspective the inner side of the sliding closure.

Referring to the drawings, 1 represents a box of any suitable material—such, for instance, as light metal—and approximating the size of a tobacco-bag. The box is provided with a main removable cover 2, provided with an opening 3 for the discharge of tobacco. Mounted to slide on the cover 2 is a closure 4, having an opening 5, which is normally out of alinement with the opening 3, but is to be placed in alinement therewith when the tobacco is to be discharged. In the under side the closure 4 has lugs 6, which pass through slots 7 in the top of the cover 2, and these lugs are connected by a cross-bar 8. The sliding closure is also provided with

lugs 9, which pass through slots 10 in the top of the cover 2, and these lugs 9 are connected by a loop-shaped bar 11, from which a spring 12 passes to a connection with an end wall of the cover, as clearly indicated in the drawings.

In operation when it is desired to discharge tobacco the closure 4 is to be slid lengthwise, so that the openings 3 and 5 will register, as clearly indicated in Fig. 1. Upon releasing the closure it will be drawn back to its normal position by means of the spring 12.

While I describe the box as designed particularly for tobacco, it is obvious that a condiment-box may be made on a similar plan—that is, instead of a single perforation in the upper closure a plurality of perforations may be formed.

Having thus described the preferred form of my invention, I claim as new and desire to secure by Letters Patent—

A box, a cover therefor, having an opening in its top, a closure slideable on the cover and having an opening adapted to register with the first-named opening, the top of said cover being provided with slots, lugs extended from the closure through said slots, cross-bars connecting with opposite lugs, and a spring connection between one of the cross-bars and an end wall of the cover.

In testimony whereof I have signed my name to this specification in the presence of two subscribing witnesses.

JOHN SUTHERLAND
